Primary Examiner — R. Johnson(74) *Attorney, Agent, or Firm* — Patterson + Sheridan, LLP(57) **CLAIM**

The ornamental design for a guitar headstock as shown and described.

DESCRIPTION

FIG. 1 is a front perspective view of a guitar headstock showing my new design.

FIG. 2 is a rear perspective view thereof.

FIG. 3 is a front elevational view thereof.

FIG. 4 is a bottom plan view thereof.

FIG. 5 is a top plan view thereof.

FIG. 6 is a rear elevational view thereof.

FIG. 7 is a left side elevational view thereof; and,

FIG. 8 is a right side elevational view thereof.

The broken lines in the figures show portions of the guitar headstock that form no part of the claimed design.

1 Claim, 6 Drawing Sheets(56)
